UNITED STATES PATENT OFFICE

2,582,134

INDIRECT HEATER FOR FLUIDS

Garman O. Kimmell and Harvey L. Chenault,
Oklahoma City, Okla., assignors to Black,
Sivalls & Bryson, Inc., Kansas City, Mo., a cor-
poration of Delaware

Application April 30, 1949, Serial No. 90,732

5 Claims. (Cl. 122—33)

1

This invention relates to a heater for liquids, particularly petroleum oils, and has for its principal object to provide a heater of the indirect type including a shell for containing a heat transfer liquid which is directly heated by an immersion type fire chamber located within the central portion of the shell and surrounded with an immersed flow tube bundle through which the liquid to be heated is circulated.

Other objects of the invention are to provide a small compact heater which combines the safety feature of less fire hazard with conservation of size and material; to provide a heater having a shell and an internal heater removably supported by one end of the shell and a tube bundle supported within the shell and removable through the opposite end for facilitating inspection and field repair; to provide an indirect type heater which operates with maximum efficiency without the use of baffles; to provide a heater that is conservative of fuel used; and to provide a greater flow tube surface for a given size heater.

In accomplishing these and other objects of the invention, we have provided improved structure, the preferred form of which is illustrated in the accompanying drawings wherein:

Fig. 1 is a perspective view of a heater embodying the features of the present invention.

Fig. 2 is a perspective view of the firebox embodied in the heater.

Fig. 3 is a perspective view of the tube bundle which is employed in the heater to circulate the liquid to be heated.

Fig. 4 is a longitudinal section through the assembled heater.

Fig. 5 is an end view of the heater.

Fig. 6 is a cross section on the line 6—6 of Fig. 4, particularly illustrating the relation of the firebox and the tube bundle.

Referring more in detail to the drawings:

1 designates a heater constructed in accordance with the present invention and which includes a cylindrical shell 2 that is arranged horizontally and supported on transverse girder plates 3 and 4 having laterally disposed flanges 5 and 6 by which the heater is adapted to be anchored on a suitable base. One end of the shell curves inwardly as at 7 to join with a coaxial collar 8 of suitable diameter for insertion of the firebox or heater unit 9, the collar 8 being provided with a laterally extending flange 10 for attaching a closure plate 11 carrying the fire or heating unit as later described. The closure plate is secured to the flange 10 by fastening devices such as bolts 12. The opposite end of the shell has an annularly

2

extending lateral flange 13 for attaching a closure plate 14 which is secured to the flange by fastening devices such as bolts 15. The firebox or heating unit includes a pair of laterally disposed and horizontally disposed U-shaped ducts 16 and 17 having upper and lower leg portions 18 and 19 welded in openings 20 and 21 that are provided in the plate 11. The leg portions are of sufficient length to extend substantially to the opposite end of the shell and are interconnected by return bends 22. The upper legs 18 are connected on the exterior side of the closure plate 11 with a breeching 23 supporting a flue or stack 24 whereby products of combustion are discharged from the heating unit. The lower legs 19 project through the plate and are connected by a cap-like housing 25 having openings therein for supporting gas burners 26 and 27 in substantially concentric relation with the legs of the ducts, the burners being supplied with a fuel such as oil or gas through a supply pipe 28 which is connected through a pressure regulator 29 and an automatic control valve 30 with the respective burners, the valve 30 being actuated responsive to temperature within the heater to automatically regulate the fuel supply in proper quantity for maintaining a predetermined temperature of the transfer medium 31 that is contained in the shell.

Insertable into the shell through the end closed by the plate 14 is a tube bundle 32 carried in supporting rings 33 and 34 having an exterior diameter slightly less than the inner diameter of the shell to permit sliding of the bundle into the shell and maintain the bundle in concentric relation with the shell. Supported by the rings and by intermediate ring segments 35 and 36 are longitudinally positioned tubes 37 arranged in circular series about the supporting rings and which have opposite ends connected by return bends 38 and 39, the return bends at one end being staggered with respect to the return bends at the other so as to provide a continuous hairpin coil for conducting flow of a liquid to be heated. The lowermost tubes comprise the terminals of the coil and the ends 40 and 41 extend through the closure plate 14 for connection with supply and discharge pipes 42 and 43, respectively, the connections being made by couplings as indicated at 44.

The shell is adapted to contain the heat transfer medium 31, for example, water, which is inserted through a water equalizing pot 45 having a tubular neck 46 connected with the interior of the shell at the top thereof as best shown in Figs. 1 and 4, the pot 45 being of sufficient capacity to

accommodate expansion of the transfer medium and to maintain the shell in completely filled condition. The top of the pot may be closed by a removable cover 47.

In assembling the heater, the tube bundle is inserted through the larger opening of the shell prior to application of the plate 14. After insertion of the tube bundle the plate 14 is bolted in leak-tight engagement with the flange 13. The heater or firebox has the leg portions thereof welded in the openings of the closure plate 11 and the upper legs 18 are interconnected by the breeching 23 which is also welded to the plate 11. The unit is then slid through the collar 8 so that the lower legs 19 of the fire ducts rest upon the supporting rings 33 and 34 and upon the segments 35 and 36 as shown in Fig. 6. When in position the closure plate 11 is connected with the flange 10 by the bolts 12.

The burners 26 and 27 are then inserted and connected with a source of gas or other fuel. The supply and discharge pipes 42 and 43 are then connected with the terminal ends 40 and 41 of the coil by the couplings 44 so that the liquid such as a petroleum oil to be heated is passed through the hairpin coils of the tube bundle. The shell is then filled with a heat transfer liquid 31, for example, water, which is supplied through the water equalizing pot 45. The burners are started and the flame and hot gases travel through the legs of the U-shaped ducts of the firebox to heat the surrounding water through the walls of the ducts. The products of combustion bring the water to a temperature set by the thermostat which affects actuation of the control valve so that the burning rate is regulated to maintain the predetermined temperature of the heat transfer medium. As the water heats, a thermosyphon circulation is set up within the shell to effect substantially uniform heating of the tube bundle through transfer of heat from the walls of the firebox ducts to walls of the tube bundles.

When it is necessary to inspect or repair the heater the fire unit may be readily removed by removing the bolts 12 and withdrawing the unit from the collar 8 without disturbing the tube bundle. If the tube bundle is to be removed, this is readily effected by removing the bolts 13 which retain the plate 14 and by withdrawing the tube bundle through the open end of the shell.

From the foregoing it is obvious that we have provided an indirect type of heater which is of small, compact construction and combines the safety feature of less fire hazard with conservation of space and material. It is also obvious that the parts are readily assembled and removed as units for inspection and repair so that any repairs which may be required may be made in the field.

What we claim and desire to secure by Letters Patent is:

1. A heater including an elongated shell having open ends, removable closure plates for closing said ends of the shell and forming with the shell a closed heat-transfer-liquid-containing space, a heating unit carried by one of the closure plates and adapted to be inserted and withdrawn through the end of the shell closed by said one closure plate, a cylindrical tube bundle adapted to be inserted into the shell through the other end for encircling the heating unit, rings supporting said tube bundle and having inner circumferences to pass over the heating unit when inserted in the shell, and means for filling said space with the heat transfer liquid for pro-

viding a common heat transfer medium between the heating unit and the tube bundle and completely surrounding the tube bundle and said heating unit.

5. A heater including an elongated shell having open ends, removable closure plates for closing said ends of the shell and forming with the shell a closed heat-transfer-liquid-containing space, a heating unit carried substantially centrally of the shell by one of the closure plates and adapted to be inserted and withdrawn through the end closed by said one closure plate, a cylindrical tube bundle adapted to be inserted into the shell through the other end in coaxial relation with the shell and in encircling relation with the heating unit, means for filling said space with the heat transfer liquid for providing a common heat transfer medium between the heating unit and the tube bundle, said heating unit consisting of a pair of U-shaped ducts having ends extending through said carrying plate, a breeching connecting one end of each duct, and burners disposed in the other end of each duct.

3. A heater including an elongated substantially cylindrical shell having an open end conforming to the inner diameter of the shell and having a smaller axial opening at the other end, removable closure plates for closing said openings and forming with the shell a closed heat-transfer-liquid-containing space, a heating unit carried by the closure plate for the smaller of said openings and adapted to be inserted and withdrawn through the smaller axial opening, a cylindrical tube bundle adapted to be inserted in the shell through the larger opening in encircling relation with the heating unit, means for filling the shell with the heat transfer liquid, said heating unit consisting of a U-shaped duct having ends extending through said smaller plate, a burner disposed in one end of the U-shaped duct, and a stack connected with the other end of the U-shaped duct.

4. A heater including an elongated shell having open ends, removable closure plates for closing said ends and cooperating with the shell in forming a closed heat-transfer-liquid-containing space, a heating unit carried by one of the closure plates and adapted to be inserted and withdrawn through the end closed by said plate, an interconnected series of hairpin coils extending longitudinally within the shell and arranged in circular series about the interior of the shell and encircling relation to the heating unit, rings supporting said coils to form a unitary structure insertable and removable through the end of the shell which is closed by the other of said closure plates, and means for filling the shell with the heat transfer liquid to completely surround said units, said rings forming a support for the heater unit.

5. A heater including an elongated shell having open ends, removable closure plates for closing said open ends of the shell and cooperating with the shell in forming a closed heat-transfer-liquid-containing space, a pair of U-shaped ducts having ends fixed in one of the closure plates substantially centrally of said closure plate for support centrally with respect to said shell, burners directed into the end of one leg of each of the ducts, a breeching connecting said other legs together, an interconnected series of hairpin coils extending longitudinally within the shell and arranged in circular series immediately adjacent the inner side of the shell, rings supporting said coils to form a unitary structure insertable and

removable through the end of the shell which is closed by the other of said closure plates, said rings having sliding support in the shell, and means for filling said space in the shell with the heat transfer liquid, said rings forming support for said legs of the ducts.
